WIRE STITCHING FEED

Joseph N. Pagliarul, Milwaukee, Wis.; Enez Pagliarul Kowalsky (Enez Kowalsky), executrix of Joseph N. Pagliarul, deceased, assignor to Inland Wire Products Company, Chicago, Ill., a corporation of Illinois

Application September 4, 1944, Serial No. 552,645

6 Claims. (Cl. 140—131)

1

This invention relates to improvements in wire stitching feeds, the feed being incorporated in a type of wire stitching machine wherein the wire is fed intermittently to a staple-forming and driving mechanism.

A general object of the invention is to provide a simple and easily adjusted wire stitcher feed mechanism which is susceptible of readjustments to compensate for wear on a wire feed segment and which is also readily adjustable to permit variations in the feed of the wire to regulate the ultimate length of the staples formed and driven by the wire stitching machine.

A more specific object of the invention is to provide, in a wire stitching machine, cooperating wire feed rollers, one of which carries a yielding feed segment cooperable with a fixed segment in the other roller, said yielding segment being readily adjustable to compensate for wear on its work surface.

Another specific object of the invention is to provide a wire stitcher feed wherein the cooperating feed rollers are formed with registrable graduations, with one of the rollers being readily adjustable to advance or retard its graduations relative to a graduation on the other roller for indicating the length of staples to be produced.

A further object of the invention is to provide a wire stitcher feed which is of very simple construction, is easily manipulated, adjusted, and serviced, is strong and durable, and is well adapted for the purposes described.

With the above and other objects in view, the invention consists of the improved wire stitcher feed and its parts and combinations as set forth in the claims and all equivalents thereof.

In the accompanying drawings in which the same reference characters indicate the same parts in all of the views:

Fig. 1 is a fragmentary front view of the upper portion of a box stapling machine embodying the improved wire stitcher feed;

Fig. 2 is an enlarged fragmentary view of that portion of the wire stitching machine with which the wire stitcher feed is associated, with the feed rollers contacting the wire prior to the advancement or feed of the wire, parts being broken away and in section;

Fig. 3 is an enlarged fragmentary detailed view, with parts broken away and in section, and similar to Fig. 2, only showing advanced positions of the feed rollers resulting in the feeding of an extent of wire;

Fig. 4 is a transverse, vertical, sectional view taken on line 4—4 of Fig. 2, and on a larger scale;

2

Fig. 5 is a transverse, vertical, sectional view taken on line 5—5 of Fig. 2 and on a larger scale; and

Fig. 6 is a fragmentary front view of the wire feed rollers and the portion of the stitching machine with which they are associated, with the rollers in a different position of adjustment than that shown in Fig. 1.

Inasmuch as the invention is concerned primarily with wire feeding mechanism incorporated in a wire stitching machine, it will not be necessary to describe in detail the entire machine in which said improvements are incorporated. As shown in Fig. 1, the machine includes a massive, hollow, vertical pedestal 8, on which is mounted a horizontal stitcher bar 9 which receives the work to be stapled. Above the stitcher bar 9 and properly spaced relative thereto is a staple cutting, forming and driving mechanism, indicated generally by the numeral 10. The moving parts incorporated in the unit 10 are controlled through the operation of cams 11 and 12 mounted fast on a horizontal clutch-controlled shaft 13. The latter is driven through connections with an electric motor (not shown).

The forward end of an elongated stretch of wire 14, preferably flat in cross-section, enters unit 10 to be successively cut into suitable predetermined lengths therein, which lengths are then bent and shaped into staples which are driven into superimposed thicknesses of paper board box walls mounted on the stitcher bar 9. The wire 14 is unwound from a reel 15 which is freely revolvably mounted on a spindle 16 supported from a frame arm 17 extending above the main portion of the machine.

A yielding wire guide and reel brake is indicated generally by the numeral 18. This member is the subject matter of my Patent No. 2,442,933 and supports the wire unwound from the reel 15 in the manner shown, guiding it to and through a wire feed check 19 and from thence between the adjacent peripheral portions of a pair of feed rollers 20 and 21, which are one of the particular features of the present invention. After the wire leaves the feed rollers, which are effective to intermittently pull desired lengths of the wire from the reel, the wire passes through a curved guide 22 and from thence to the staple-forming and driving mechanism 10.

A wire straightener 59 comprises a U-shaped bracket adjustably seated on and embracing any selected portion of the outer arm of the wire guide 18. It is held in a selected adjusted position by a clamping bolt 60 having its shank portion

threaded through a tapped opening in the intermediate wall of the member 59 and impinging against a selected portion of the member 18. The spaced and projecting side flanges 62 of the member 59 carry therebetween a stud 63 on which a roller 64 is revolvably mounted. The wire 14, because of its being wound on the reel 15, may come from the reel in a bent or deflected condition, and in this condition it is extended over the curved portion of the outer arm of the wire guide. It is desirable that the wire be straightened before it reaches the subsequent mechanisms for proper formation of staples, and to that end the roller 64 on the member 59 engages the stretch of wire 14 as it is advanced and deflects the same in a direction so as to take out the bends or irregularities therein. By loosening the clamping bolt 60 and shifting the unit 59 upwardly or downwardly along the outer arm of the guide 18, the point of contact of the roller 64 with the wire may be varied and regulated in accordance with the condition of the wire and the extent of the bends or irregularities therein which are to be straightened or eliminated.

The wire feed check 19, previously referred to and best shown in Figs. 1 and 6, comprises an outer barrel 67 having a vertical bore therethrough which houses the bored shank of a stem 68, the latter extending exteriorly of and above the barrel 67 and having a headed portion 69 between the lower surface of which and the top of the barrel, there is a coiled spring 70. Within the barrel 67 and surrounding the stem 68 is a downwardly outwardly tapered cavity 71 which houses, on opposite sides of the stem 68, a pair of ball bearings 72, the latter both projecting through recesses in the stem 68 and engaging therebetween the stretch of wire 14 which is passed axially through the bore of the stem and through the lower end of the barrel 67. When there is a downward or feeding pull on the wire 14, as imposed by the feed rollers 20 and 21, the stem 68 is urged downwardly in the bore of the barrel 67, and this permits the ball bearings 72 to follow the enlarged contour of the cavity 71, whereby said ball bearings are not pressed into clamping contact with the wire 14, permitting free feeding of the wire in the direction of advancement. The depression of the stem 68 is against the force exerted by the spring 70. Should there be an undesired upward pull imposed on the wire 14 due to retrograde movement of the reel, the wire might undesirably shift upwardly and thereafter prevent the formation of proper length staples, save for the wire feed check 19. With the arrangement described, as there is an upward pull on the wire, there is an immediate resilient lifting of the stem 68 to an extent which will confine the ball bearings 72 within upper or reduced portions of the cavity 71 whereby said ball bearings will be forced inwardly relative to the stem recesses to cause the ball bearings to clampingly engage the wire 14 therebetween to positively and automatically prevent undesired upward movement of the wire. Should it be desired to shift the wire upwardly slightly for any particular reason, the feed wire check can be released through manually pressing down on the headed portion 69 of the stem 68 against the tension of the spring 70, to shift the ball bearings into an enlarged portion of the cavity 71 and to permit the wire 14 to move upwardly therebetween.

The feed rollers 20 and 21 are driven in unison by means of gears 23 and 24, tightly carried re-

spectively by the inner ends of the hubs of the feed rollers 20 and 21. The gear 24 for the inner feed roller is positively driven through the medium of the usual gearing which extends to and derives its power from the shaft 13.

To obtain an intermittent feed, only a portion of the peripheries of the feed rollers 20 and 21 are employed. Thus, the feed roller 21 has within its wire receiving peripheral groove a fixed feed segment 25. The companion feed roller 20 has within its peripheral groove an adjustable and yielding feed segment 26, best shown in Figs. 2 and 3, and comprising a relatively thin shank portion 26' and a thicker work section 26'', the outer surface of the latter being outwardly offset from the corresponding surface of the portion 26'. The shank portion 26' of said feed segment 26 is pivotally mounted on a wheel-carried pin 27. The work section 26'' of said feed segment is constantly urged radially outwardly by a coiled spring 28 confined within a recess in the feed roller 20. A set screw 29 is adjustably threaded into the wheel 20, radially inwardly with respect to the groove of said wheel and the outer end portion of said set screw underlies the inner end of the pivotal feed segment 26. The adjustment of said set screw relative to the feed segment determines the amount of yielding pivotal movement said feed segment may have.

During operation of the wire feeding mechanism it is, of course, evident that the outer engaging surface of the work section 26'' of the feed segment 26 may be subjected to wear which will effect its grip and efficiency. The mounting of said feed segment and its arrangement is such that after wear has impaired said feed segment, the effective surface thereof may be reground and a resetting of the set screw 29 will compensate for any reduced thickness in the portion 26'' of the feed segment due to grinding.

In Fig. 4 there is illustrated the manner in which the feed roller 20 is assembled with its associated parts. The driving gear 23 is fast on the reduced inner end of a central hub member 30 and is additionally secured thereto by a pin 31. The forward end portion of the hub member 30 is slightly reduced, and the feed roller 20 is keyed onto said reduced portion of the hub member. The entire assembly is secured together by an axial bolt 32 whose outer end has threaded thereon a nut 33. When the nut is tightened, an interposed plate 34 clampingly bears against the outer end of the hub member.

Fig. 5 illustrates the manner in which the complementary feed roller 21 is assembled with its associated parts. The reduced inner end portion of a hub member 35 has fast thereon the operating gear 24, previously mentioned, a pin 36 aiding in the securing of the gear. The forward end portion of the hub member 35 is slightly reduced, and the feed roller 21 is keyed onto said reduced portion. The feed segment 25 on said feed roller 21 is in fact an inwardly directed flange on a roller plate 37, and said plate is angularly adjustable relative to the feed roller 21 to vary the disposition of the segment flange 25. For that purpose the plate 37 is provided with an outwardly projecting manipulating knob 38. Normally, the plate 37 is clamped tightly against the outer face of the feed roller 21 so as to turn therewith by means of a bolt 39 and a clamping plate 40. However, when the bolt 39 is loosened, by means of the knob 38, the plate 37 may be turned circularly to advance or retard the feed segment flange 25 relative to the feed

roller 21. It is, in this connection, convenient to have a face portion of the plate 37 formed with spaced graduations 41, and the registration of a desired graduation 41 with a graduation 42 on the face of the complementary feed roller 20 will determine the length of contact of the effective portions of the feed segments 25 and 26, and hence the amount of intermittent feed of the wire 14 and the ultimate length of staple to be formed.

Assuming that the staple-cutting, forming and driving mechanism 10 has been set for operation on staples of a desired length, then the disc 37 is set so as to register the selected graduation 41 with the graduation 42 on the feed roller 20, to provide for the length of intermittent wire feed. With the machine then in operation and through the train of gears and the roller carried meshing gears 23 and 24, the feed rollers 20 and 21 will revolve toward each other in opposite directions. The extent of wire 14 passes between the meeting peripheral portions of the feed rollers 20 and 21 and, due to the grooved formation of the feed rollers, turning movement of the feed rollers is ineffective to engage and advance the wire until the portion 26" of the feed segment 26 comes into contact with the feed segment 25 of the feed roller 21. As long as said portions of the feed segments are in contact, the wire will be squeezed therebetween and will be pulled downwardly a desired advanced extent, suitable for the formation of a staple. There will be cessation in the advancement of the wire when the feed segments are out of contact. In Fig. 2 there is illustrated the relation of the feed segments to the wire before the effective portions of the feed segments are in mutual engagement, and Fig. 3 illustrates the relationship of the parts just as the intermittent feed is about to terminate, with the portion 26" of the feed section 26 terminating its contact with the feed segment 25. The yieldability of the feed segment 26 permits proper clamping engagement of the same with the wire and the set screw 29 is important in regulating the proper position of the feed segment and limiting its amount of yielding pivotal movement.

Mounted on a bracket portion of the machine with its open upper end alined with a tangent to the meeting peripheries of the wire feed rollers 20 and 21, is a curved wire feed guide 22. This member is adapted to receive the wire after it passes the feed rollers and to direct it to the staple cutting and forming mechanism 10. Throughout the length of the member 22 there is a curved internal cavity through which the extent of wire 14 passes. The upper end of the wire receiving portion of the member 22 is enlarged, as at 83, for better receiving and directing the wire. The major portion of the wire receiving extent of the curved wire guide is open along its outer side, as at 84, and the cavity is substantially oval to conform with the flat shape of the wire to eliminate friction and clogging and to enhance the feeding of the wire. The open construction of the guide permits the guide cavity to be easily rid of dirt which might lodge therein or surface material rubbed from the moving wire, it being appreciated that an accumulation of such material within the wire guide cavity might clog the same and prevent free or easy movement of the advancing wire. The open side to the cavity makes the construction practically self-cleaning and permits ready lubrication of the interior of the cavity and the wire passing therethrough. It will further be observed that a flattened side 75

flange portion of the member 84 is removably bolted to a supporting portion of the machine by bolts 85, whereby removal of the unit is permitted for easy repairs, cleaning or replacement.

5 The improved wire stitching feed mechanism very adequately provides for the intermittent feed of the wire in desired lengths and the feed rollers are readily adjustable and removable from their assemblies for repairs and replacements. Wear 10 which may occur on the effective surface of the segment portion 26" may be easily remedied and compensated for. The improved wire stitching feed mechanism is simple in its operation and construction and is well adapted for the purposes 15 described.

What is claimed as the invention is:

1. An apparatus for intermittently feeding wire embodying a pair of positively driven feed rollers, a feed segment pivotally mounted adjacent the periphery of one roller, said feed segment having an outwardly projecting gripping portion and an inwardly offset portion which limits the length of feed of the wire, a rotatively adjustable gage disc mounted on the other roller, a feed segment integral with said disc and extending adjacent a peripheral portion of its roller, means for resiliently urging the gripping portion of the first-mentioned feed segment toward the other feed segment, and adjustable means carried by the 20 first-mentioned roller and contacting the pivotally mounted feed segment for limiting the yielding pivotal movement of said feed segment.

2. In a wire stitching machine having a wire-carrying reel and an elongated guide for engaging 25 and supporting wire immediately uncoiled from the reel, a bearing adjustably mounted on the guide for engaging and deflecting wire uncoiled from the reel and moved along the guide to straighten said wire.

3. In a wire stitching machine having a wire-carrying reel and an elongated, eccentrically curved guide directly associated with the reel for engaging wire immediately upon the same being uncoiled from the reel, a bearing longitudinally 30 adjustably mounted on the guide for engaging and deflecting wire uncoiled from the reel and moved along the guide to straighten said wire.

4. In a wire stitching machine having a wire-carrying reel and an elongated eccentrically curved guide for engaging wire immediately upon the same being uncoiled from the reel, a bracket 35 longitudinally adjustably mounted on the guide, and a roller journaled in the bracket and contactable with surface portions of the wire uncoiled from the reel and moving along the guide to straighten said wire.

5. An apparatus for intermittently feeding wire embodying a pair of positively driven feed rollers, a rotatively adjustable gage disc mounted on one 40 of said rollers, a rigid feed segment carried by said disc adjacent a peripheral portion of said roller, the other feed roller being formed with a peripheral groove, a feed segment intermediately pivotally mounted within said groove, a spring bearing against one end portion of said segment to yieldingly urge said end portion of the segment outwardly beyond the periphery of its roller for gripping cooperation with the feed segment of the other roller, and an adjustable stop carried by the 45 peripherally grooved feed roller engageable with the other end of the pivotal feed segment to limit the outboard pivotal movement of the first-mentioned end of said segment.

6. An apparatus for intermittently feeding wire embodying a pair of positively driven feed rollers,

a rotatably adjustable gage disc mounted on one of said rollers, a rigid feed segment carried by said disc adjacent a peripheral portion of said roller, the other feed roller being formed with a peripheral groove, a coiled spring mounted within the last-mentioned feed roller and projecting into the peripheral groove, a feed segment intermediately pivotally mounted within said groove, said feed segment having an outwardly projecting relatively thick gripping portion and an inwardly offset relatively thin portion which limits the length of feed of the wire, the undersurface of the thick gripping portion of said feed segment being engaged and yieldingly urged outwardly by said spring for gripping cooperation with the rigid feed segment of the first-mentioned roller, and an adjusting screw radially threaded into the peripherally grooved feed roller at the base of the groove and removed from the spring, the outer end of said screw being adjustably contactable with the undersurface of the reduced end of the pivotal feed segment to limit the outward pivotal movement of the gripping portion of said feed segment.
